UNITED STATES PATENT OFFICE.

WILLIAM A. LYNCH, OF CANTON, OHIO.

COMPOSITE BOARD.

SPECIFICATION forming part of Letters Patent No. 759,899, dated May 17, 1904.

Application filed August 8, 1902. Serial No. 118,918½. (No model.)

To all whom it may concern:

Be it known that I, WILLIAM A. LYNCH, a citizen of the United States, residing at Canton, in the county of Stark and State of Ohio, have invented certain new and useful Improvements in Composite Boards, of which the following is a specification, reference being had therein to the accompanying drawings.

This invention relates to an improvement in composite boards, the object being to produce board-like articles which can be built up of relatively weak pieces of wood of little cost and which when completed shall be greatly increased in strength and able to withstand high transverse strains which would tend to break the boards either when applied on lines transverse to the fibers or on lines parallel with them. Boards of this kind are especially adapted for use in the construction of heavy floorings, as the bottoms of automobiles, the floors of cars, the walls of freight-cars, &c.

In the drawings, Figure 1 shows in plan a section of a composite board embodying my improvements. Fig. 2 is a cross-section on the line *xx* of Fig. 1. Fig. 3 is an end view of the strips or pieces of wood of the upper set. Fig. 4 is a similar view of the pieces or strips of the lower set. Fig. 5 shows the corrugated steel. Fig. 6 is a plan view of a piece of the latter.

I have selected for illustration a board-like structure and the component parts shown in the drawings.

35 A A are a series of counterpart wooden strips, and B B indicate others of like character.

A' and B' indicate strips or pieces of wood similar in essential character to those at A and 40 B, but differing therefrom in width. In practice a relatively thin wooden board or strip, such as shown by the dotted lines at *a'* and the full lines *a''*, is subjected to the action of a planing or equivalent machine and a series of 45 grooves *a''*, formed therein, the tongues or ribs *a* being left. The component strips or pieces can be made in large quantities ready for building up composite boards of any desired width.

50 D indicates a plate of sheet metal uniformly

and evenly corrugated, as shown in Fig. 5, this shaping of the steel being accomplished by crimping-rollers or other suitable machines. When it is desired to build up the composite article, a section of the steel is taken 55 and into the grooves or corrugations on the under side are fitted a series of the grooved wooden strips B B', sufficient in number to give the desired width. Then a series of bars or strips A A' are similarly placed in the corrugations or depressions in the upper side. By preference I so arrange the lower row of wooden strips and the upper row that I "break joints," as shown in Figs. 2 and 3. After the parts have been fitted together they are 60 subjected to pressure sufficient to effect a tight and firm union. This union may be maintained by the use of a suitable adhesive material, although originally I prefer to effect a permanent rigidity of fastening by means 65 of screws or nails, as shown at E, some passing through the lower layer of wood, then through the sheet-steel and into the wood of the upper layer, and others being passed downward from the upper wood through the steel to 70 the lower. From an examination of the drawings it will be seen that I in this way produce from the initial relatively thin and relatively 75 weak strips of wood a board-like device of considerably greater thickness and reinforced 80 in such way that it is increased in strength to a great extent. If a stress should be exerted downward in such way as to carry or tend to carry the fibers at lines between the side edges 85 downward and parallel to said side edges, this is resisted by the overlapping of the tongues *b b* of the lower pieces of wood upon the tongues or projections *a* in the upper pieces—that is to say, the tendency of those on the upper pieces to spread is resisted by the 90 wedging or crowding action of those on the lower pieces, and the intervening plate of crimped or corrugated steel not only distributes this balancing of the tendencies to bend, but itself serves as a resistant.

95 What I claim is—

1. A composite board or bar having an upper piece or pieces of wood formed with ribs or projections *a* and intervening grooves or depressions, a lower piece or pieces of wood 100

having similar ribs and grooves, and the interposed corrugated steel strip pressed into the grooves or recesses in the wooden strips, the ribs of one piece of wood fitting into the 5 grooves or recesses in an opposite piece of wood, substantially as set forth.

2. A composite board or bar having an upper series of pieces of wood, each formed with one or more ribs or tongues α , and recesses at 10 the sides of each rib, a lower series of pieces of wood, each piece having one or more similar ribs and recesses, and the interposed corrugated sheet-metal strip extending continuously across both the upper and the lower 15 series of pieces, and having its corrugations pressed into the grooves or corrugations in the wood, the wood pieces of the upper series being arranged to break joints in relation to the pieces of the lower series, substantially as 20 set forth.

3. The composite board or bar having an up-

per series of pieces of wood each formed with one or more ribs or tongues α , and recesses or grooves at the sides of each rib, a lower series of pieces of wood each having one or more 25 similar ribs and recesses, one or both of said series having one or more relatively wider and one or more relatively narrower strips, and the interposed corrugated sheet-metal strip pressed into the grooves or recesses in 30 the wooden strip, the said relatively narrow strips being arranged substantially as set forth to have the lines of contact of the strips of one series break joints with the strip of the other series.

In testimony whereof I affix my signature in presence of two witnesses.

WILLIAM A. LYNCH.
